CLAIM

The ornamental design for a briefcase smart screen, as shown and described.

DESCRIPTION

FIG. 1 is a front, right and top perspective view of a briefcase smart screen in a closed state, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, right and top perspective view of the briefcase smart screen in an open state.

FIG. 11 is a rear, left and bottom perspective view of the briefcase smart screen of FIG. 10.

FIG. 12 is a front elevation view of the briefcase smart screen of FIG. 10.

FIG. 13 is a rear elevation view of the briefcase smart screen of FIG. 10.

FIG. 14 is a left side elevation view of the briefcase smart screen of FIG. 10.

FIG. 15 is a right side elevation view of the briefcase smart screen of FIG. 10.

FIG. 16 is an enlarged top plan elevation view of the briefcase smart screen of FIG. 10.

FIG. 17 is an enlarged bottom plan elevation view of the briefcase smart screen of FIG. 10.

FIG. 18 is an enlarged view of detail 18 in FIG. 10.

FIG. 19 is an enlarged view of detail 19 in FIG. 11.

FIG. 20 is an enlarged view of detail 20 in FIG. 17.

FIG. 21 is another front, right and top perspective view of the briefcase smart screen of FIG. 10 in an alternate state; and,

(Continued)

FIG. 22 is another front, right and top perspective view of the briefcase smart screen of FIG. 10 in an alternate state. The broken lines depict portions of the briefcase smart screen that form no part of the claimed design. The dot-dash broken lines in FIGS. 1, 9-11, and 17-20 depict the boundaries of the enlargements that form no part of the claimed design.

1 Claim, 22 Drawing Sheets
